UNITED STATES PATENT OFFICE

EDWARD N. JACOBI, OF MILWAUKEE, WISCONSIN, ASSIGNOR TO BRIGGS AND STRATTON CORPORATION, OF MILWAUKEE, WISCONSIN, A CORPORATION OF DELAWARE

CYLINDER LOCK

Application filed October 23, 1925. Serial No. 64,380.

This invention has for its object to provide a cylinder lock of the slide tumbler type so constructed that the tumbler slides will be guided throughout their movements and not likely to bind notwithstanding spring pressure exerted thereon.

Another object of the invention is to provide the tumbler slides of a lock of this character with actuating springs bearing thereon at points between the guide surfaces and as close to the center of the tumbler slide as is feasible without interfering with the movements of the slide.

Another object of the invention is to provide a lock cylinder with a central cavity passing diametrically therethrough, in the walls of which are formed the grooves constituting the tumbler guides and the spring cavities, all so arranged as to produce a cylinder suitable for die casting.

Another object of the invention is to provide a lock cylinder of the centrally open type with a stationary bridge or key guide across the opening to prevent deflection of the key by the action of the spring tumblers when moving the key in and out of the cylinder.

Another object of the invention is to provide a lock of this character with a guide shoulder for guiding the serrated edge of the key by engaging a guide shoulder on the key spaced from said edge and thus confining the key between the guide for said guide shoulder and the guide for the straight edge of the key.

Another object of the invention is to perfect the details of construction of a lock of this type to make it strong and durable but inexpensive to manufacture.

With the above and other objects in view the invention consists in the cylinder lock as herein claimed and all equivalents.

Referring to the accompanying drawings, in which like characters of reference indicate the same parts in different views,

Fig. 1 is a side view of a lock cylinder constructed in accordance with this invention;

Fig. 2 is the front end view thereof;

Fig. 3 is the rear end view thereof;

Fig. 4 is a longitudinal sectional view;

Fig. 5 is the bottom view;

Fig. 6 is a section on the plane of line 6—6 of Fig. 1;

Fig. 7 a section on the plane of line 7—7 of Fig. 5;

Fig. 8 a section on the line 8—8 of Fig. 1;

Fig. 9 a similar view with the tumbler slide and spring removed;

Fig. 10 is a top view of the lock cylinder; 60

Fig. 11 a longitudinal sectional view thereof with tumblers and springs removed;

Fig. 12 is a bottom view showing a key bridge of a modified form, and

Fig. 13 is a transverse sectional view on 65 the line 13—13 of Fig. 12.

In these drawings, 20 indicates a die cast lock cylinder, which is provided with tumbler slides 21 extending transversely therethrough to engage in opposite grooves 22 of 70 the lock case in which it fits as usual, the presence of a key 23 passing longitudinally through the lock cylinder and transversely through the tumbler slides to lift them against the action of springs to various degrees so that they lie flush with the walls of the cylinder, being required to permit the cylinder to be turned to effect the release of the lock. 75

The lock cylinder is provided with an opening 24 extending longitudinally thereof and diametrically therethrough and having the key pass lengthwise through it. Opposite grooves 25 in the side walls of the opening 24 form guides for the tumbler slides 21, 85 which have central openings 26, through which the key passes.

In order that the tumbler slides may bear with pressure on the serrated edge of the key, each is provided with a spring 27 housed 90 within the cylinder in the cylindrical recess 28 and engaged by an outwardly projecting arm 29 on the edge of the tumbler slide. To avoid weakening the structure, the several spring recesses 28 are arranged alternately on opposite sides of the opening 24 and to permit of die casting said recesses extend in one direction to the surface of the cylinder. In order to position the spring 27 as close as 95 possible to the center line of the tumbler slide 100

its recess 28 is made to open directly into the opening 24 and thus materially reduces the length of the guide groove 25 on this side of the tumbler, but compensation is provided for this interruption of the guide groove 25 by extending the arm 29 into a guide groove 30 in the wall of the recess, thus giving the tumbler slide opposite edge bearings at both ends to prevent it from binding and also lateral bearings on both sides of both ends and at both edges to prevent lateral dispacements by the pressure of the key in passing therethrough. The spring recesses 28 open directly to the opening 24 with parallel side walls and the springs 27 are seated on the closed ends thereof and are located as close as possible to the edge of the tumbler slides but are prevented from frictional engagement therewith by pairs of beads 31 which project from the side walls of the recesses for a short distance, as best seen in Figs. 9 and 11.

The cylinder is provided with a longitudinal key opening 32 as usual and with a key-receiving slot 33 at its front end to receive the shoulders of the key, by the engagement of which the key turns the lock cylinder to cause the crank lug 34 on the rear end of the lock cylinder to operate mechanism not shown. To facilitate the entry of the key its end is pointed as usual and a conical cavity 35 is formed in the front of the lock cylinder in a position to lead the point of the key. At the entrance to the key opening it is guarded by wards 36 projecting inwardly and requiring the key to be of a shape to pass between them, but more particularly it is provided with a guide shoulder 37, which is continued at the rear end of the key opening. This guide shoulder receives a shoulder 38 of the key and co-operates with the bottom of the key opening in definitely and accurately positioning the key during its entire movement in the cylinder from the moment its end is inserted in the opening 32 and its shoulder 38 engages the shoulder 37 and its straight edge engages the bottom key guiding surface. In order to guide the key and prevent it from binding in the key slot by taking an angular position therein on being inserted, the longitudinal opening 24 of the lock barrel is crossed by one or more bridge pieces 39 with their upper edges close to but slightly below the level of the straight edge of the key when it is seated. The point end of the key by engaging these bridge pieces is cammed into its proper line so that it will not become jammed or bound. As seen in Fig. 5, these bridge pieces 39 extend angularly across the opening 24 so as to join with the walls of the grooves which are offset. This is the preferred form in which said bridge pieces are made integral with the die cast lock cylinder, but it is obvious that one or more of such bridge pieces may be

formed separately and set into slots formed in the cylinder, as in Figs. 12 and 13, wherein the bridge piece 39' slightly bent laterally is let into slots 40.

The operation of a cylinder lock of this type is too well understood to require explanation, but the construction and arrangement is such that it is possible to form the lock cylinder as an integral die casting requiring no machining and still affording adequate guide surfaces for the spring-pressed tumbler slides that will not permit of their tilting or binding or of their lateral displacement or of spring interference therewith and providing for a guiding of the key throughout its movements preventing it from binding or from taking a false position that would interfere with the proper operation of the lock. The present construction accommodates large springs for the tumblers without materially weakening the cylinder construction.

What I claim as new and desire to secure by Letters Patent is:

1. In a die cast lock cylinder having a diametrical opening for tumbler slides and provided with grooves in the walls of the opening, tumbler slides fitting in said grooves, there being a recess in the wall of the opening in line with one of the grooves for each slide, arms on the tumbler slides projecting into said recesses, springs seated in said recesses and bearing on the arms, there being grooves in the walls of the recesses into which the ends of the arms project to guide the tumblers in their movements.

2. In a die cast lock cylinder having a diametrical opening with grooves in its walls, tumbler slides slidably fitting in the grooves, and springs seated in the cylinder and bearing on the tumbler slides between the points of engagement of said slides with the grooves.

3. A die cast lock cylinder having a diametrical opening therethrough and provided with guide grooves in its opposite walls, tumbler slides fitting in said guide grooves, one of the guide grooves for each slide being recessed, a coiled spring seated in said recess and extending along the edge of the slide, there being a continuation of the guide groove in the bottom of the recess, and an arm projecting from the slide across the recess and into the continuation of the guide groove and engaging the end of the spring.

4. A die cast lock cylinder having a diametrical opening with opposite guide grooves in its walls, tumbler slides fitting in the guide grooves, one of the guide grooves for each tumbler slide being recessed to form a spring housing and having a continuation of the guide groove formed in its wall, an arm projecting from the edge of the tumbler slide across the recess and into the continuation of the groove, a coiled spring seated in the recess and extending along the edge of the tumbler slide and bearing on the arm, and

opposite projections on the walls of the recess near the spring seat for spacing the spring from the edge of the tumbler slide.

5. A die cast lock cylinder having a diametrical opening with guide grooves in its walls, tumbler slides fitting in the guide grooves, one of the guide grooves for each tumbler slide being recessed, a coiled spring seated in the recess, an arm projecting from the edge of the tumbler slide engaged by the spring, and opposite projections on the walls of the recess near the spring seat for spacing the spring from the edge of the tumbler slide.

6. A lock cylinder having a diametrical opening with guide grooves in its walls, plate tumblers fitting in the guide grooves, there being a longitudinally extending key opening through the cylinder and key openings in the tumblers through which a key having a straight edge, a serrated edge and a longitudinally extending guide shoulder is adapted to pass, a guide shoulder formed in that portion of the key opening receiving the serrated edge of the key, said shoulders cooperating with the straight edge of the key and its bearing in the key opening to maintain a straight line movement of the key in the cylinder, the lock cylinder being die cast in one piece to obtain uniformity.

7. A die cast lock cylinder having a diametrical opening therethrough provided with grooves in its walls, there being a key opening extending longitudinally through the cylinder for the reception of a key having a straight edge and a serrated edge, tumblers fitting in the grooves and provided with openings through which a key passes when inserted in the cylinder key opening, and a bridge piece extending across the diametrical opening of the cylinder integral with the walls of the grooves and terminating close to the straight edge of the key to form a guide for the key.

8. A die cast lock cylinder having a diametrical opening therethrough provided with grooves in its walls, tumblers fitting in said grooves, there being a key opening extending longitudinally through the lock cylinder for the reception of a key having a straight edge, a serrated edge and a shoulder, a shoulder in the key opening corresponding with the shoulder on the key to fit therewith, and a bridge piece extending across the diametrical opening of the lock cylinder and terminating approximately in the line of the straight edge of the key to cooperate with said shoulders in guiding the key in its passage through the diametrical opening.

9. A die cast lock cylinder having a diametrical opening therethrough with grooves in its walls, tumblers fitting in said grooves, there being a key opening extending longitudinally through the lock cylinder for the reception of a key having a straight edge and a serrated edge adapted to pass through open-

ings in the tumblers, there being a slot across the lock cylinder with its edges coinciding with the edges of the said grooves, and a bridge piece let into said slot and terminating close to the straight edge of the key to guide the key in its passage through the diametrical opening.

10. A lock cylinder having a diametrical opening with guide grooves in its walls, plate tumblers fitting in the guide grooves and having key openings registering with a longitudinally extending key opening extending through the cylinder for the reception of a key having a straight edge, a serrated edge and a shoulder, a guide shoulder formed in the portion of the key opening receiving the serrated edge of the key at both ends of the diametrical opening, said guide shoulder corresponding with the shoulder formed on the key, and said shoulders cooperating with the straight edge of the key and its bearing in the key opening to maintain a straight line movement of the key in the cylinder, the lock cylinder being die cast to obtain uniformity.

11. In a die cast lock cylinder having a longitudinal key slot and a longitudinally extending diametrical opening therethrough with tumbler grooves in its wall, preformed spring pressed plate tumblers fitting in said grooves across the opening and having openings forming a key passageway through them through which passes a key having a cam end and adapted to be inserted in said key slot for the retraction of the tumblers, and a bridge extending across the opening of the lock cylinder and cooperating with the cam on the end of the key for guiding the key in its passage through the tumbler openings.

In testimony whereof, I affix my signature.
EDWARD N. JACOBI.
